United States Patent

Des. 235,157
Patented May 20, 1975

235,157

TOY BLOCK

Eugene J. Echterling, Woodland Hills, Calif., assignor to Questor Corporation, Toledo, Ohio

Filed Jan. 24, 1973, Ser. No. 326,368

Term of patent 14 years

Int. Cl. D21—01

U.S. Cl. D34—15 FF

FIG-1

FIG-4

FIG-3

FIG. 1 is a perspective view of a toy block showing my new design;

FIG. 2 is a top plan view thereof, the bottom plan view being identical;

FIG. 3 is a left side elevational view thereof, the side opposite being identical; and,

FIG. 4 is a front elevational view thereof, the side opposite being identical.

I claim:

The ornamental design for a toy block, as shown and described.
